CLAIM

The ornamental design for a vertical axis wind turbine light ornament, as shown and described.

DESCRIPTION

FIG. 1 is a perspective view of a vertical axis wind turbine light ornament, showing our new design;

FIG. 2 is a second perspective view thereof;

FIG. 3 is a front elevation view thereof;

FIG. 4 is a rear elevation view thereof in the direction of line 4-4 of FIG. 7;

FIG. 5 is a left side elevation view thereof in the direction of line 5-5 of FIG. 7;

FIG. 6 is a right side elevation view thereof in the direction of line 6-6 of FIG. 7;

FIG. 7 is top plan view thereof;

FIG. 8 is a bottom plan view thereof;

FIG. 9 is an enlarged front elevation view;

FIG. 10 is a cross section view taken along line 10-10 of FIG. 9;

FIG. 11 is a cross section view taken along line 11-11 of FIG. 9;

FIG. 12 is a cross section view taken along line 12-12 of FIG. 9;

FIG. 13 is a cross section view taken along line 13-13 of FIG. 9;

FIG. 14 is a cross section view taken along line 14-14 of FIG. 9;

FIG. 15 is a cross section view taken along line 15-15 of FIG. 9; and,

FIG. 16 is a cross section view taken along line 16-16 of FIG. 9.

In the drawings, the broken lines illustrate portions of the article which form no part of the claimed design.

1 Claim, 7 Drawing Sheets
